FERNAND BOYER, OF PARIS, FRANCE.

THREAD-FEEDING DEVICE FOR TUFTED-FABRIC LOOMS.

Application filed May 19, 1925, Serial No. 31,274, and in Switzerland May 22, 1924.

Looms for mechanical manufacture of tufted carpets are already known. Such machines however are not altogether suitable for the manufacture of colored carpets as the devices for this purpose are too imperfect. It is chiefly owing to this drawback that tufting machines have been rarely adopted at all in this industry, and the manufacture of colored tufted carpets has 10 remained hand work to this day.

This invention relates to a device for tufted carpet looms for the preparation and supply of tufting material of different colors to one and the same tufting tool, whereby 15 it is possible to produce colored tufted carpets on the machine.

The device is characterized by: movable guides or feeders in which endless pile threads of different colors are situated; 20 Jacquard mechanism which controls the movable guides in any desired sequence; at least one gripping member intended to seize the pile threads and pull them out of the guides to the required length; a transfer device which is provided with take-up members which take these pile threads from the gripping member and supply them to the tufting tools or devices of the carpet machine; a cutting device by which the pile 25 threads situated in the take-up members, are cut to the length required before they are supplied to the tufting tools of the machine.

The accompanying drawings illustrate by 30 way of example a construction of the apparatus by means of which tufting thread of six different colors can be supplied to each tufting tool.

Fig. 1 is a side elevation of the upper portion of a machine embodying my present invention.

Fig. 1^a is a similar view showing the lower portion thereof.

Fig. 2 is an elevation showing the controlling devices for the movable guides.

Fig. 3 is a similar view taken at right angles to that shown in Fig. 2.

Fig. 3^a is a partial plan of a pattern card which is shown in edge elevation in Fig. 3.

Fig. 4 is an elevation illustrating the cutting devices and the means for operating the same.

Fig. 5 is a plan view of the cutting devices as illustrated in Fig. 4.

Fig. 6 is an enlarged sectional view of 55 the guide members showing the same in the position as illustrated in Fig. 3.

Fig. 7 is a sectional plan of the parts as shown in Fig. 6.

Fig. 8 is an edge view of the movable guides showing the same in the position as 60 illustrated in Fig. 2, but on an enlarged scale.

Fig. 9 is an enlarged side elevation of the movable guides showing the same in one position.

Fig. 10 is a similar view showing these parts in another position.

Fig. 11 is also a view similar to Figs. 9 and 10 showing the parts as illustrated in a still further position.

Fig. 12 is a side elevation illustrating the transfer devices as associated with the movable guides.

Fig. 12^a is a continuation of a lower portion 75 of these transfer devices.

Fig. 13 is a sectional elevation illustrating the operation of the transfer devices showing the same in one position.

Fig. 14 is another view of these transfer devices showing the same in another position.

Fig. 15 is a sectional elevation of the transfer devices.

Fig. 16 is a side elevation on an enlarged scale illustrating a part of the transfer devices.

Fig. 17 is an end elevation of the parts as illustrated in Fig. 16.

Fig. 18 is an elevation of the transfer devices as illustrated in Fig. 15, but showing 90 the same on an enlarged scale.

Fig. 19 is a view similar to Fig. 18 with one of the movable bars removed for the purpose of illustration.

Fig. 20 is a plan view illustrating the 95 transfer devices as shown in Figs. 18 and 19.

Fig. 21 is a plan of the cutting devices as illustrated in Fig. 5, but showing the same in a different position and on an enlarged scale.

Fig. 22 is a sectional elevation of the cutting devices taken at right angles to the position shown in Fig. 4, but on an enlarged scale.

Fig. 23 is a plan of the cutting devices as 105 shown in Fig. 5, but on an enlarged scale.

Fig. 24 is a partial elevation of the cutting devices as shown in Fig. 4 but on an enlarged scale.

Fig. 25 is an elevation and partial cross 110 section illustrating the cutting devices and the means for operating the same.

Fig. 26 is an elevation of the parts shown in Fig. 25 taken at right angles to the position as illustrated in Fig. 25, and

Fig. 27 is a perspective view illustrating the transfer devices.

For each tufting tool, the machine is provided with a guide or feeder (Figures 1, 2, 3, 9, 10, 11, 12, 13) rotatable about a horizontal axis and comprising six movable guides for the six threads 39 of different colors. The threads 39 are supplied from spools 39' (Figure 11), pass through the guide 37, round the pins 37' of the guide 37 and are situated in recesses 37² of the latter; they are arranged above each other in a single vertical plane. By turning the feeder under the control of the Jacquard mechanism, the outgoing section of any desired thread 39 is brought into the vertical plane M—M (Figure 9) containing the axis of rotation, in which the thread can be seized by the clamping member 51—52.

All the guides 37 are mounted on a spindle 40 (Figures 1, 3, 9, 10, 11, 12) which can be rocked by an eccentric through levers 41, 42 and a connecting rod 43. According to the thread which is to be seized by the corresponding clamping member 51, 52, each guide 37 makes an oscillation of a variable amplitude in one direction. To that end, under each guide 37 and in the spindle 40 is provided a hole or bore in which is placed a spring 44 which acts on a ball 45 and presses it against the inner surface of the hub of the guide so that the latter is caused by the spindle 40 to participate in the latter's rotation if it does not offer excessive resistance. At the circumference of the guide 37 are provided six teeth 38 which cooperate with a movable pawl or catch 36 controlled by the Jacquard mechanism, in such a manner that, depending upon the tooth 38 engaged by the pawl, one or another of the threads 39 is brought into the plane M—M as depicted in Figure 9. The circumferential pitch of the teeth 38 corresponds to the oscillations of the pawl 36, and their distance from the axis of the spindle 40 changes, between the uppermost and the lowermost one, to an extent required by the amplitude of oscillation of the pawl 36.

When a working period is completed, each guide 37 will be in neutral position, that is to say none of its threads 39 will be in the vertical plane M—M (Figure 9). In each working period, the spindle 40 is rotated in an anti-clockwise direction and drives with it the guides 37 under the action of the springs 44. Each guide 37 remains then in engagement with that of the teeth 38 of the corresponding pawl 36, which is determined by the amplitude of oscillation of the said pawl and therefore by the Jacquard mechanism. As soon as the lever and the spindle 40 are turned in the other

direction, the guides again driven by the balls 45, return to the neutral position shown in Figure 9. In order to ensure that the differently set guides will always reach the same neutral position when they are moved back, there is provided behind them a stop 46 (Figure 9) against which they are all pressed. To this end, recesses 48 (Figures 9, 10, 11) are provided in the guides which recesses guide one and the same rod 49 rigidly secured to the spindle 40. When the spindle rotates in an anti-clockwise direction, no guide 37 will be affected or interfered with by the rod 49, but during the return of the spindle 40, each guide 37 whether it be lagging behind owing to the resistance of the thread 39 coming from the spools 39' or for any other reason, will be forced into the neutral position (Figure 9) by the said rod 49.

The Jacquard mechanism is provided with a color pattern which controls all the guides 37 and takes the form of a card 2 (Figure 1). This card is unwound from a cylinder 1, passes over guide rollers 3, 4 over transport rollers 5, 6, through the space between the guide rods 7, 8, over a guide roller 9 and is wound again on a cylinder 10. It cooperates with cross wires 11 (see also Figures 2, 3, 6, 7, 8) of which there are six, one above each other, for each feeder 37. The card is divided into fields or areas corresponding to the series of cross wires 11. Each field contains corresponding perforations 13 (see Figure 3 bis) for each cross wire and blank spaces. The transport rollers 5, 6 with the card 2 can be advanced to the position 2—14, out of the position of rest depicted by Figures 1 and 7, in order to bring the card 2 in engagement with the cross wires 11. The cross wires 11 which happen to be opposite the corresponding perforations, will retain their position, whilst the cross wires 11 striking a non perforated portion of the card, will be forced back by the card 2 (for instance the 5th cross wire from the top in Figures 3 and 6). During the return of the transport rollers 5, 6 to the position of rest shown in Figure 1, these rollers are turned by means of a feed device 15 and 16 mounted in front of them; in this way a new area of the card 2 will be brought in front of the cross wires 11 and at the next operation will again act on the wires. The field and spacing of the perforations in the card 2, the advance and the feed, correspond of course to the field and spacing of the cross wires 11. The card 2 is mounted on the transport rollers 5 and 6 in such a manner that it is positively driven and cannot move accidentally.

Behind the cross wires 11, in guides 17 and 18 are arranged vertically shiftable pull hooks, 19 (Figures 1, 2, 3, 6, 7, 8), the number of which is equal to that of the

guides 37. They are provided at one side with a pull lip 20 and at the other side with a push lip 21. Their up and down movements are produced by a slide 22 which is operated in a corresponding manner by an eccentric by means of a lever 23 and a lifting rod 24. The hooks are in a position of rest normally as shown by dot and dash lines in Figure 6. When the card 2 has been advanced and has operated the cross wires 11, the slide 22 will be moved downwards. Each pull hook 19 participates in this downward movement, partly by gravity and partly under the action of a spring herein-after described, until its push lip 21 strikes a cross wire that has been pushed back (Figures 3 and 6). The slide 22 descends to such an extent that the pull hooks 19 can bring back to inoperative position even the lowest cross wires 11. After each working period, the slide 22 returns again to the position of rest shown in dotted lines in Figure 6 and moves with it to the position of rest all the pull hooks 19 whether set to a lower or higher position.

Above the pull hooks 19 is mounted a back slide 25 slotted like a comb, to span the pull hooks 19 which can thus be moved towards the back of the cross wires 11 and also away from the same (Figures 6 and 7). It is coupled by a link 27 to a lever 28 which is connected by means of the rod 29 to the transport mechanism of the card 2 (Figure 1). As soon as the card 2 is moved towards the cross wires 11, the back slide 25 is moved away from their back, so that the card 2 can push back the correct cross wires 11. The diameter of each cross wire is greater than the width of the corresponding slots in the slide 25 so that when the card 2 returns to the position of rest shown in Figure 1, the back slide 25 will also be moved towards the cross wires 11 and will push them back into the position of rest shown in Figure 7, so that all cross wires 11 will be again rendered inoperative, and at the next advance of the card 2, the process will be repeated.

From the bottom end of each pull hook 19, a flexible connection 30 (cord, wire cable or the like) leads to a catch lever 31 which is mounted so as to oscillate on a common spindle 32 (Figures 1, 3, 9-12). The connection 30 leads over rollers 33 which are rotatably mounted on a supporting plate 34 (Figures 2 and 3). The pitch of the catch levers 31 is independent in the lateral direction from the pitch of the pull hooks, as the connection 30 and the arrangement of the rollers 33 allows it. Each catch lever 31 is always pulled downwards by a tension spring 35, and in that way the connection 30 is always held quite taut. If under the action of the card 2, the pull hook 19 is set to one or another cross wire 11 of

a series, the corresponding catch lever 31 will make a corresponding oscillation. The catch hook 36 mounted on the other arm of the catch lever 31, is thus caused to oscillate to the right and returns to the original position as soon as the slide 22 returns the pull hook 19 to the position of rest.

Under each guide 37 is arranged the gripping member 51-52 comprising a fixed gripping jaw 51 and the movable jaw 52 (Figures 1, 3, 9, 10, 11, 12 and 13). The movable jaws 52 of the grippers are rigidly secured to one and the same spindle 53 which is rotatably mounted on the fixed part 51. By turning this spindle 53, the grippers are opened and closed; this opening and closing is effected by means of an eccentric lever 54, a connecting rod 55 and a lever 56 laterally secured to the spindle 53. The grippers 51-52 are vertically movable and shown in the position of rest in Figure 9. When the guide 37 is turned in the manner already stated, and a thread 39 is brought into the vertical plane M-M, the corresponding gripper will be moved upwards, and the movable jaw 52 opened. The corresponding thread 39 is now between the two jaws which have reached the highest position in Figure 10. In this position the movable jaw 52 closes and the thread 39 is thus gripped. The gripper 51-52 descends then into the low position shown in Figure 11, carrying with it the thread 39 and pulling it through the guide 37.

On the left of the grippers 51-52 are arranged levers 57 which belong to the transfer device and are secured to a spindle 59 rotatably mounted in eccentric levers 58 (Figures 1, 9, 10, 11 and 12). The levers 57 are provided at the bottom end with a lug 60 (see also Figure 15) on which is mounted a roller 61. On the said roller acts an eccentric lever 62. Owing to the action of the eccentrics on the levers 62 and 58, the transfer levers 57, together with all the parts mounted on them and described later, are rocked in the direction of the arrow or in the opposite direction to an angle of about 90° (single positions are shown in Figures 1 and 12).

At the upper end of the transfer levers 57 are mounted, on a fixed connecting rail or bar 63, bifurcated take off members 64, as well as on a movable bar 65 bifurcated delivery members 66 (Figures 1, 12, 13, 15, 16, 17, 18 and 19). The movable bar 65 lies flat on the connecting bar 63 and is held by covering guides 67. On the movable bar 65 is mounted a roller 68 which engages with a slot in a bell crank lever 69 mounted on a transfer lever 57. On the same transfer lever 57 there is a second bell crank lever 70 and the bell crank levers 69 and 70 are connected by a rod 71. The bell crank lever 70 is again pivoted by means of a rod

72 to an eccentric lever 73. This rod 72 can be twisted, that is to say its two end portions can be turned relatively to each other about the longitudinal axis of the rod. For this purpose a pivot pin 75 is passed through a bushing 74 on the said rod. When the eccentric lever 73 acts by means of the connecting rod 72 on the bell crank lever 70, the rod 71 will also rock the bell crank lever 69, and in that way reciprocate in the longitudinal direction the movable bar 65. Owing to the particular arrangement of the rod 72 and to the possibility of twisting it by means of the device 74-75, the bar 65 can be moved at any moment whatever the position of the transfer lever 57, may be as for instance when the said lever makes an oscillation to 90° as already mentioned.

20 The movable rail or bar 65 has however, in addition to its longitudinal movement, to make also a radial movement. To this end, between the said bar and the fixed connection bar 63 is mounted a crank 76, the shaft 25 77 of which is arranged in the connection bar 63, and the crank pin 78 in the movable bar 65 (Figures 15, 18 and 19). This crank arrangement is repeated several times on the connection bar 63, to suit the length.

30 It is thus obvious that as soon as the movable bar 65 is moved to the right, it will make a radial movement in such a manner that the delivery members 66 will be moved away from the take off members 64 (Figure 18), whilst the reverse movement of the bar 65 brings them together (Figures 15 and 19). The radial movement of the bar 65 takes place in such a manner that both in the open position shown in Figure 18, 40 and in the closed position shown in Figure 19, the slots of the take off members 64 and the slots of the delivery members 66 are brought above each other. A change takes place however; that is to say the delivery member 66 which in the open position (Figure 18) is in a straight line under a take off member 64, comes in the closed position (Figure 19) under the first take off member 64 on its left.

50 If as already stated and illustrated in Figures 10, 11 a thread 39 is seized by the gripper and drawn, it will be in a straight line between the guide 37 and the gripper 51-52. The transfer levers 57 then swing with the opened bar 65, into the position shown in Figures 11, 12, the thread being placed into a take-up member 64 and a delivery member 66, the position shown in Figures 11, 18 being thus obtained. The movable bar 65 passes at the same time radially to the left and grips the thread 39 in a double angle between the take-up members 64 and the delivery members 66 (Figures 16, 17 and 19). During the movement 60 of the bar 65 to the left, the gripper 51, 52

rises and opens slightly (Figure 12) so that the bottom portion of the thread 39 is released.

The thread 39 taken up and gripped in this manner, must be severed at the top in order to enable the guide 37 to return to the neutral position shown in Figure 9. For this reason, on the right hand side, behind the vertical plane M—M, are arranged horizontal shears 79-81 (Figures 9, 10, 11, 12, 13, 21, 22, 23), the bottom blades of which are secured to a support 80. The upper blades 81 are rotatable about pins 82, on the bottom blades 79 and are pressed against the latter by means of springs 83. The support 80 together with the shears 79-81 mounted on the same are horizontally adjustable in suitable guides and can be moved by means of eccentric levers 84 and of a pivoted link or rod 85 (Figure 1) towards and away from the vertical plane M—M (see Fig. 9). In the position of rest, the shears according to Figures 9 and 10 are in such a position that they do not interfere with the gripping members 51-52. The upper blades 81 of the shears are guided between the studs 86 of a closing device 87 which is arranged parallel to the support 80. This device must take part in the horizontal movement of the said support towards or away from the plane M—M and can be reciprocated in a longitudinal direction (see also Figure 5). To the closing device 87 is secured a driver 88 which engages over the head of a closing lever 89 (Figures 4, 22-24). The head of the closing lever 89 is pivoted in the driver 88 and the closing lever 89 is so arranged that the driver 88 can slide over the head of the lever 89 when the support 80, with all the parts mounted on it, makes a movement towards or away from the plane M—M. By means of an eccentric lever 90 and of a pivot connecting rod 91 (see also Figure 1) which transmits the movement of the eccentric lever 90 to the closing lever 89, the closing device 87 can be reciprocated in the longitudinal direction mentioned, and in that way the shears closed or opened. Owing to the sliding of the driver 88 on the head of the closing lever 89, the shears can be opened and closed, whether they be in the position of rest, Figures 9 and 10, or moving forwards or backwards.

When thus, as already stated, the drawn or pulled out thread 39 has been gripped according to Figure 11 between the take-up members 64 and the delivery members 66 according to Figure 19, the shears 79-81 are moved from the position shown in Figure 10 into the position shown in Figure 11, whereupon they will be closed by the means described, and in that way will sever the thread 39 at the top. The guide 37 is then free to return to the neutral position. Each pair

of shears cuts at a time two threads; Figure 23 shows diagrammatically the position of the threads 39 before and after the advance of the shears.

5 The severed thread 39 assumes thereafter the position shown in Figure 19, that is to say it is held fast in a double angle between the take off members 64 and the delivery members 66, and projects with the upper 76 ends beyond the take off members 64. These projecting ends are still in the way, and are therefore turned over once more, as shown in Figures 16 and 17. At the top on the rigid connecting bar 63 is arranged a bridge provided with slots 92 for the purpose of taking-up the ends of the threads (Figures 16-20). On the support 80 for the shears is arranged an angle bar 93 which is provided with stud like pusher-pins 94 bevelled downwards in front (Figures 9-13). The pitch of these pushers 94 harmonizes exactly with the slots 92. On the angle bar 93 are arranged, exactly above the pushers 94, angular recesses 95 (Figures 21-23) into which 75 the threads 39 are introduced at the moment of cutting shown in Figure 11. The support 80 together with all the parts mounted on it, then executes a further movement forward, from the position shown in Figure 11 into 80 the position shown in Figures 12, 13, owing to which the upper ends of the threads 39 are turned over and pressed by the pushers 94 into the slots 92 and remain in that position (Figures 16 and 17) after the support 80 has 85 again returned to the position of rest (Figures 9 and 10). In this way, the thread 39, completely ready for tufting or knotting, is situated in the take off members arranged on the transfer levers 57; by swinging the levers 95 40 57, it is brought to the corresponding tufting tool (Figures 1 and 12). Each time, a pair of hooks 96 of this tool passes in the well known manner over a pair of warp threads 97 into the intermediate space of the take-off member 64, rises a little, seizes on the return the thread 39 and pulls its ends over a pair of warp threads 97, whereupon tufting or knotting (Figure 14) takes place. It is obvious that the movable bar 65 opens slightly at the moment when the hooks 96 lift the tufting thread 39 out of the take off members 64 and delivery members 66 so that the thread 39 is released and comes out easily.

The support member 80 together with the 55 shears 79-81 mounted on the same are horizontally movable in suitable guides 111 and are moved by means of eccentric levers 84 and a pivoted link or rod 85 as indicated in Figs. 1, 25 and 26. This movement of the support member and the shears is towards and away from the vertical plane indicated at M-M. The guides 111 slide on rods 112 (see Fig. 26) which by means of screw nuts 113 are secured to a support 114. This support 114 is secured by means of screws 115

or otherwise to a part 116 of the machine frame. These members are illustrated in Fig. 1 and more clearly shown in Fig. 25. The support member 80 is fixed by means of screws 117 to the guides 111. There are also 76 guides 119 fixed by means of screws 118 to the shear supports 80. It will be noted that the movable shear support member 80 forms a sort of bridge between the left and right hand members of the machine, it being 75 further noted that in Fig. 25 only the left hand side member is illustrated. The eccentric lever 84 is connected with a lever 84^a by means of a shaft 120 journaled in bearings 121. The lever 84^a is provided with a roller 122 adapted to bear on the surface of an eccentric 123, and as will be understood, the rotation of this eccentric, through the members just described, causes a horizontally reciprocating motion of the guides 111 and the 85 parts connected thereto.

The working of the apparatus is as follows:

The transport rollers 5 and 6 advance, whereby the card 2 pushes back given cross 90 wires 11. The pull hooks 19 descend then as far as the cross wires 11, so that the catch levers 31 are set in a corresponding manner. The guides 37 rotate and remain in engagement by means of the corresponding catch tooth 38, with the catch hook 36. Thus the colored threads 39 determined by the card, are brought into the plane M-M. The grippers 51-52 rise, seize the threads 39 and pull them out downwards. The transfer levers 57 move the take off members 64-66 100 over the pulled threads and firmly grip the latter. The bottom ends of the threads 39 are then released by the grippers 51-52. The support 80 advances, whereby the threads 39 are brought between the shear blades 79-81 and cut by them at a suitable moment. During continued advance of the support 80, the upper ends of the threads 39 are turned over and fixed. The transfer levers 57 then swing the threads thus prepared for tufting, within reach of the usual tufting tools which take them off and tuft them in the well known manner into the ground fabric of the carpet. All the parts 110 return at a suitable moment to their position of rest, or neutral position, whereupon the whole process is repeated.

In the construction described, it has been 115 assumed that there are as many separate grippers 51-52 as there are feeders 37. But a common gripper could be provided, the jaws 51-52 of which are held in accordance with the length of the guides 37 arranged side by side; all the pile threads 120 brought by the guides 37 into the vertical plane M-M would in these circumstances be seized by the common gripper.

The tufting thread may be of wool or other material.

What I claim is:

1. In an apparatus for tufted carpet looms for the preparation and supply of tufting material of different colors to one and the same tufting tool in manufactured colored tufted carpets the combination with movable guides in which are arranged endlessly supplied pile threads of different colors, of a Jacquard mechanism which controls the movable guides in any desired sequence of colors, a gripper member adapted to seize a pile thread and pull it out from its guide to the length required, a transfer device provided with take off members which take the pile thread from the gripper and supply it to a tufting tool of the apparatus, and a cutting device which severs the pile thread to the length required before it is supplied to the tufting tool.
2. In an apparatus for tufted carpet looms for the preparation and supply of tufting material of different colors to one and the same tufting tool in manufactured colored tufted carpets the combination with movable guides in each of which are arranged endlessly supplied pile threads of different colors and which are constituted for each tufting tool by a rotatable feeder in which as many different colored pile threads are taken up, as there are colors to be used, of a Jacquard mechanism which controls the movable guides in any desired sequence of colors and by the control of which the rotary feeder is so moved that it brings a given pile thread into a position to be gripped each rotary feeder being provided on its circumference with teeth, the number of which is equal to that of the pile threads, a rotatable pawl cooperating with the teeth of the rotary feeder and controlled by the Jacquard mechanism, in such a manner that the rotation of the feeder from a neutral position has a different amplitude according to the particular pile thread, a gripping member adapted to seize a pile thread and pull it out from its guide to the length required, a transfer device provided with take off members which take the pile thread from the gripper and supply it to a tufting tool of the apparatus, and a cutting device which severs the pile thread to the length required before it is supplied to the tufting tool.
3. In an apparatus for tufted carpet looms for the preparation and supply of tufting material of different colors to one and the same tufting tool in manufactured colored tufted carpets the combination with movable guides in each of which are arranged endlessly supplied pile threads of different colors and which are constituted for each tufting tool by a rotatable feeder having teeth in which as many different colored pile threads are taken up, as there are colors to be used, of a Jacquard mechanism which controls the movable guides in any desired sequence of colors and by the control of which the rotary feeder is so moved that it brings a given pile thread into a position to be gripped, a rotatable pawl cooperating with the teeth of the rotary feeder and controlled by the Jacquard mechanism, in such a manner that the rotation of the feeder from a neutral position has a different amplitude depending upon the particular pile thread, means for returning the various guides to the exact neutral positions, a gripping member adapted to seize a pile thread and pull it out from its guide to the length required, a transfer device provided with take-up members which take the pile thread from the gripper and supply it to a tufting tool of the apparatus, and a cutting device which severs the pile thread to the length required before it is supplied to the tufting tool.
4. In an apparatus for tufted carpet looms for the preparation and supply of tufting material of different colors to one and the same tufting tool in manufactured colored tufted carpets the combination with movable guides in each of which are arranged endlessly supplied pile threads of different colors, and which are constituted for each tufting tool by a rotatable feeder in which as many different colored pile threads are taken up as there are colors to be used, of a Jacquard mechanism which controls the movable guides in any desired sequence of colors and by the control of which the rotary feeder is so moved that it brings a given pile thread into such a position to be gripped, a rotatable pawl cooperating with the teeth of the rotary feeder and controlled by the Jacquard mechanism, in such a manner that the rotation of the feeder from a neutral position has a different amplitude depending upon the particular pile thread, means for returning the various guides to the exact neutral positions, a gripping member adapted to seize a pile thread and pull it out from its guide to the length required, a transfer device provided with take-up members which take the pile thread from the gripper and supply it to a tufting tool of the apparatus, and a cutting device which severs the pile thread to the length required before it is supplied to the tufting tool.
5. In an apparatus for tufted carpet looms for the preparation and supply of tufting material of different colors to one and the same tufting tool in manufactured colored tufted carpets the combination with

movable guides in each of which are arranged endlessly supplied pile threads of different colors, and which are constituted for each tufting tool by a rotatable feeder having teeth, and in which as many different colored pile threads are taken up, as there are colors to be used, of a Jacquard mechanism which controls the movable guides in any desired sequence of colors and by the control of which the rotary feeder is so moved that it brings a given pile thread into a position to be gripped, a rotatable pawl cooperating with the teeth of the rotary feeder, a longitudinally movable member controlled by the Jacquard mechanism for controlling the movement of the rotatable pawl, in such a manner that the rotation of the feeder from a neutral position has a different amplitude depending upon a particular pile thread, means for returning to the neutral position the longitudinally moving member, a gripper member adapted to seize a pile thread and pull it out from its guide to the length required, a transfer device provided with take-up members which take the pile thread from the gripper and supply it to a tufting tool of the apparatus, and a cutting device which severs the pile thread to the length required before it is supplied to the tufting tool.

6. In an apparatus for tufted carpet looms for the preparation and supply of tufting material of different colors to one and the same tufting tool in manufactured colors tufted carpets the combination with movable guides in each of which are arranged endlessly supplied pile threads of different colors, of a Jacquard mechanism which controls the movable guides in any desired sequence of colors, a gripping member adapted to seize a pile thread and pull it from its guide to the length required and constituted by two jaws movable relative to each, and which can be brought jointly close to and away from its guide in order to seize a desired pile thread and pull it out to the required length, a transfer device provided with take off members which take the pile thread from the gripper and supply a pile thread to the tufting tool of the apparatus, and a cutting device which severs the pile thread situated in the take off members to

the length required before it is supplied to the tufting tool.

7. In an apparatus for tufted carpet looms for the preparation and supply of tufting material of different colors to one and the same tufting tool in manufactured colored tufted carpets the combination with movable guides in each of which are arranged endlessly supplied pile threads of different colors, of a Jacquard mechanism which controls the movable guides in any desired sequence of colors, a gripping member adapted to seize the pile thread and pull it from the guide to the length required, a transfer device provided with take-up members which take the pile thread from the gripper and supply it to the tufting tool of the apparatus, and a cutting device which severs the pile thread to the length required before it is supplied to the tufting tool of the apparatus, said cutting device having a number of blades arranged on a single support which can be brought close to the guides and gripping member or moved away from the same in order not to interfere therewith.

8. In an apparatus for tufted carpet looms for the preparation and supply of tufting material of different colors to one and the same tufting tool in manufactured colored tufted carpets the combination with movable guides in each of which are arranged endlessly supplied pile threads of different colors, of a Jacquard mechanism which controls the movable guides in any desired sequence of colors, a gripping member adapted to seize a pile thread and pull it from the guide to the length required, a transfer device provided with take-up members which take the pile thread from the gripper and supply it to a tufting tool of the apparatus, and a cutting device which severs the pile thread to the length required before it is supplied to the tufting tool of the apparatus, and means pertaining to the transfer device adapted to turn over the ends of the cut pile thread that still project from the members of said transfer devices.

In testimony whereof I have affixed my signature.

FERNAND BOYER.
